TYPEWRITING MACHINE

Original Filed April 1, 1930

UNITED STATES PATENT OFFICE

WILLIAM GRAEPEL, OF RIDGEWOOD, NEW YORK, ASSIGNOR TO ROYAL TYPEWRITER COMPANY, INC., OF NEW YORK, N. Y., A CORPORATION OF NEW YORK

TYPEWRITING MACHINE

Original application filed April 1, 1930, Serial No. 440,849. Divided and this application filed February 25, 1931. Serial No. 518,272.

This invention relates to new and useful improvements in typewriting machines generally, although more particularly to means for positively retaining certain normally 5 movable parts of the machine against movement during shipment of the machine, and constitutes a division of my co-pending application Serial No. 440,849, filed April 1, 1930, for improvements in typewriting machines.

Rough handling of typewriters, particularly when being shipped or when being carried, is very injurious to the movable parts of the machine, and therefore one of the 15 objects of the invention is to provide releasable means for retaining the carriage against longitudinal or letter space movement.

With these and other objects in view which will more fully appear, the nature of the invention will be more clearly understood by following the description, the appended claims, the several views illustrated in the accompanying drawings, in which

Figure 1 is a detail side elevation of a 25 typewriting machine embodying my invention, and

Figure 2 is a detail perspective view showing my improved means for retaining the carriage against longitudinal or letter space 30 movement.

Referring to the accompanying drawings, I have shown my invention as applied to the well known Royal portable typewriting machine, although it will be understood that 35 the invention may be applied to typewriting machines of other manufacture. The typewriting machine as shown in the drawings embodies a main frame A having side plates 5 and a rear plate 6, and the usual shift frame which supports the carriage B through the medium of upper and lower rails 7, 7 and 8, 8 which are respectively fixed to the carriage B and to the shift frame. Disposed 40 between each pair of upper and lower rails 7 and 8 is a plurality of anti-friction balls 7^a and these balls are each mounted within a pinion 7^b the teeth of which engage a series of openings 7^c and 7^d respectively formed in 45 the upper and lower rails.

Mounted on the main frame A is the usual center stop D.

In order to lock the carriage against end-wise or longitudinal movement, I have provided a lock pin F which is preferably 55 formed of a wire bent into U-shape to provide a connecting portion 9 and spaced legs 10 and 11, the former being shorter than the latter. This wire is of a diameter sufficiently 60 small to permit the legs 10 and 11 to be inserted in registering pairs of openings 7^c and 7^d when the carriage is in its central position. This lock pin embraces the central stop D and consequently the pin is not only firmly held in operative position but is also 65 prevented from turning. The shorter leg 10 is provided with a crimp 12 which forms a stop for cooperation with the central stop D to prevent accidental displacement of the stop pin. Attached to the lock pin F by a 70 cord 13 is a tag 14 on which is suitable printed matter, the cord and tag serving as a means to assist in withdrawing the lock pin from its operative position.

I claim:

1. In a typewriting machine, the combination with a main frame, of a carriage mounted thereon, cooperating rails respectively provided with openings adapted to register when the carriage is in its central 80 position, and a lock pin located in said registering openings to retain the carriage against longitudinal movement.

2. In a typewriting machine, the combination with a main frame, of a carriage mounted thereon, cooperating rails respectively fixed to the frame and to the carriage and respectively provided with openings adapted to register when the carriage is in 85 its central position, a center stop for the carriage, and a U-shaped stop pin embracing the center stop and having its legs located in said registering openings to retain the carriage against longitudinal movement.

3. In a typewriting machine, the combination with a main frame, of a carriage mounted thereon, cooperating rails respectively fixed to the frame and to the carriage and respectively provided with open- 100

ings adapted to register when the carriage
is in its central position, a center stop for
the carriage, and a U-shaped stop pin em-
bracing the center stop and having its legs
5 located in said registering openings to re-
tain the carriage against longitudinal move-
ment, one leg of the stop pin being provided
with a stop arranged for cooperation with
the center stop to retain said stop pin against
10 accidental displacement.

In testimony whereof, I have hereunto
subscribed my name.

WILLIAM GRAEPEL.
